UNITED STATES PATENT OFFICE.

CHARLES B. WARE, OF PHILADELPHIA, PENNSYLVANIA.

AUTOMATIC VALVE-ROD-ADJUSTING DEVICE.

Application filed January 17, 1921. Serial No. 437,783.

To all whom it may concern:

Be it known that I, CHARLES B. WARE, a citizen of the United States, residing in Philadelphia, Pennsylvania, have invented 5 an Automatic Valve-Rod-Adjusting Device, of which the following is a specification.

One object of my invention is to provide a device for automatically taking up lost motion developing from wear in the valve gear of an internal combustion engine, thereby to prevent the loosening of parts and the development of noises in the apparatus; a further object being the provision of convenient 15 means for resetting the automatic device after the latter has moved through the limit of its action.

The invention will be more readily understood from the attached drawings, in which:

20 Figure 1 is a vertical section of the valve mechanism of an internal combustion engine, showing my device in use;

Fig. 2 is a vertical section of my device assembled but detached from the valve gear;

25 Figs. 3^a to 3^e are detached perspective of the device;

Fig. 4 is a detached perspective of a portion of the device illustrating the method of operation;

30 Fig. 5 is a detached perspective of the portion of the device illustrated in Fig. 4, showing the parts in original starting position; and

Fig. 6 is a vertical section illustrating the 35 application of the device to overhead valve mechanism.

With reference to the drawings, 1 indicates the engine casing, in which is mounted a valve 2, the stem 3 of which extends downwardly 40 through a suitable vertical bearing or guide 4, the bottom of the stem overlying the top of a vertically disposed push rod 5, said push rod being mounted in a suitable vertical bearing or guide 6 on the engine frame. The 45 push rod 5 has at its lower end a small wheel or roller 7, which is retained by means of a spring which exerts a downward thrust upon the push rod, against the surface of a cam 8 upon the cam shaft 9 of the engine, said cam being such that as the shaft 9 rotates, the push rod is reciprocated vertically. A spring 10 is confined in the present instance between the under side of the bearing member 4 and a collar or spring rest 11 se-

cured to the lower end of the valve stem 3, 55 said spring 10 tending to retain the valve 2 to its seat.

Carried in the top of the push rod 5 and constituting an interposed element between the valve stem and the push rod is the device which constitutes the subject of the present invention. This device comprises in its preferred form a base element 12 having a portion 12^a adapted to fit within a suitable recess 5^a in the top of the push rod 5, said element 12 comprising in addition a cylindrical collar-like member 13, the upper face of which is shaped to form two inclined cam surfaces 13^a, 13^b. A pin or rod 14 extends upwardly through the center of the said 70 cam member 13.

Provided with a central aperture 16 and adapted to receive the pin 14, which extends therethrough, is a second cylindrical cam member 15, the under face of which is 75 shaped to form inclined cam surfaces 15^a, 15^b, similar to the cam surfaces 13^a of the member 13 and adapted to co-operate with said latter cam surfaces in a manner to be described hereinafter.

The device further comprises a top element 17 having a bore 18 extending inwardly and centrally of the under side and adapted to receive the upper end of the pin 14, and having a threaded recess 19 in the top thereof for the reception of a threaded bolt 20, in the manner most clearly shown in Fig. 2. A lock nut 21 is also provided whereby the said bolt may be retained in any desired position in the said member 17. 90

A spring washer 22 is preferably interposed between the elements 15 and 17, the purpose of this washer to be set forth hereinafter. A casing 23 is provided which rests upon the flange 12^b of the member 12, and which is adapted to be secured to said member by means of a suitable pin or set screw 24 extending through an aperture in the base of the casing 23 and into a recess formed in the side of the member 12. The casing 100 23 has also at the top an inwardly extending lug 25 which is adapted to enter a vertically slotted recess or way 26 in the side of the top member 17, thereby providing for vertical movement of the said top member relative to the casing, but preventing any rotational movement of the top member 105 therein. It will be noted that the members

12 and 17 and the casing 23 when assembled are rotationally immovable with respect to each other.

Established in the side of the casing 23 5 is an inclined slot 27, and extending through the said slot and beyond the outer surface of the casing 23 is a pin 28 which is suitably secured to the member 15.

When the elements of the device are assembled as shown in Fig. 2, a cavity 29 is 10 formed by adjoining recesses in the members 12 and 15, said cavity 29 being formed between the walls of the cam elements. Established within this cavity 29 is a coiled spring 15 30, the ends of which are suitably secured to the members 12 and 15, respectively, the 20 said ends of the spring in the present instance being established within suitable recesses in the said elements, as most clearly shown in Fig. 2.

The spring 30 tends to rotate the said members 12 and 15 in opposite directions, and the interengaging cams 13^a and 15^a are such that when the said elements are 25 rotated relatively by the said spring, the element 15 rides upwardly upon the element 12, in the manner shown in Fig. 4, which shows the said elements in an extreme separated condition which they assume after being 30 rotated by the said spring. The said slot 27 is inclined at the same angle to the horizontal as the surfaces of the cams 13^a and 15^a, so that the said slot causes no impediment to the free rotation of the element 15 35 in the casing. The casing and the slot are so disposed with respect to the cam surfaces 13^a and 15^a that when the pin 28 is at the lower end of the slot the two elements 15 and 13 are close together, as shown in Fig. 40 5, but when the said member is revolved sufficiently to carry the pin 28 to the upper end of the slot, further rotational movement of the parts is prevented by the pin abutting the said upper end, leaving the elements in 45 the position shown in Fig. 4. By manually returning the pin 28 to the lower end of the slot, the said element 15 is revolved and is brought back to the low position shown in Fig. 5.

50 In applying this device, the member 12 is suitably attached to the upper end of the push rod and the bolt 20 is so adjusted that it lies in contact with the bottom of the valve stem when the valve is on its seat. 55 There is thus no lost motion between the cams upon the shaft 9 and the valve. As the parts become worn, however, the device expanding acts automatically to take up the play developing from the said wear, the 60 spring 29 operating to rotate the element 15, and the rotational movement of the element 15 with respect to the element 12 elevating the said element 15 and carrying the top member 17 upwardly in the casing. The 65 said spring washer 22 interposed between the

top element and the element 15 holds the said elements slightly separated so that allowance is made for the expansion of the parts when they become heated. When the parts are worn so that the device is extended to 70 the limit of its movement and the pin 28 reaches the upper end of the slot 27, the device may be reset by manually returning the pin to the lower end of the slot, and by readjusting the bolt 20 so that it again bears 75 against the bottom of the valve stem when the valve is on its seat.

In Fig. 6 I have illustrated the device as applied to an "overhead" valve gear, the device in this instance being as before attached to the top of the push rod and being interposed between the said push rod and the reach rod 31, which extends to the rocker arm 32, said rocker arm in turn engaging in this case the upper end of the valve stem 85 33 of the valve 34.

It will be understood that considerable modification is possible with no departure from the essential features of the invention. Thus for example, many full equivalents of 90 the cams illustrated may be employed with considerable modification in the form of the device.

I claim:

1. In a device of the character stated, the 95 combination with a casing, of a pair of elements mounted in said casing end to end, said elements being adapted for relative rotational movement and for relative translational movement toward and from each 100 other and having their adjacent ends so formed that relative rotational movement effects said movement of translation, means for preventing rotation of one of the elements in the casing, and a spring tending to 105 rotate the other element in the casing.

2. In a device of the character stated, the combination with a casing, of a pair of elements mounted in said casing end to end and adapted for relative translational movement toward and from each other, means for preventing rotation of one of the elements in the casing, a spring tending to 110 rotate the other element in the casing, said elements being so formed on their adjacent 115 faces that rotation of said spring-actuated element effects relative translational movement of the elements, and resilient means in said casing adapted to exert pressure against the outer end of one of said elements.

3. The combination of a reciprocating valve element, a driven actuating element for said valve, and a device interposed between said elements comprising a casing, an element fixed in said casing, an element movable in said casing both rotationally and axially with respect to said fixed element and normally in contact with said fixed element, means whereby rotational movement of said element effects movement thereof 120 125 130

axially of the said fixed element, a spring tending to rotate said movable element, a slot in said casing, and a pin secured in said movable element and extending through the 5 slot.

4. The combination of a reciprocating valve element, a driven actuating element for said valve, and a device interposed between said elements comprising a casing, an 10 element fixed in said casing, an element movable in said casing both rotationally and axially with respect to said fixed element and normally in contact with said fixed element, means whereby rotational movement 15 of said element effects movement thereof axially of said fixed element, a spring tending to rotate said movable element, a third element mounted in said casing and free to move longitudinally therein, means preventing 20 rotation of said third element in the casing, and a member carried by said third member and extending beyond the end of the casing and adjustable longitudinally in said element.

25 5. The combination of a reciprocating valve element, a driven actuating element for said valve, and a device interposed between said elements comprising a casing, an element fixed in said casing, an element movable in said casing both rotationally and axially with respect to said fixed element and normally in contact with said fixed element, means whereby rotational movement 30 of said element effects movement thereof

axially of said fixed element, a spring tending to rotate said movable element, a third element mounted in said casing and movable longitudinally therein, means for preventing rotation of said third element in the casing, and resilient means interposed between said 35 movable and third elements and tending to retain them apart.

6. The combination of a reciprocating valve element, a driven actuating element for said valve, and a device interposed between said elements comprising a casing, an element fixed in said casing, an element movable in said casing both rotationally and axially with respect to said fixed element and normally in contact with said fixed element, 40 interengaging cam surfaces upon said fixed and movable elements whereby rotational movement of the latter element effects movement thereof axially of said fixed element, a spring tending to rotate said movable element, in the casing, a slot in said casing, a 45 pin secured in said movable element and extending through the slot, a third element mounted in said casing and movable longitudinally therein, a spring washer interposed 50 between said movable element and the said third element, means preventing rotation of said third element in the casing, and an adjustable set screw mounted in the end 55 of said third element and extending beyond 60 the end of the casing.

CHARLES B. WARE.
